DENTAL CLEANSING AND MASSAGE DEVICE

Harry Logue Welker, Williamsport, Pa.

Application April 17, 1934, Serial No. 721,016

1 Claim. (Cl. 15—227)

This invention relates to a dental cleaning and massaging device. It has for its general object the provision of a flexible member of the finger cot type having a rubbing strip for cleansing the teeth and stimulating the gums, and carrying a charge of tooth paste which is made available incident to the employment of the device in its rubbing or massaging capacity.

Another object of the invention is to provide 10 a device of the character described in which the rubbing strip defines a space within which is lodged a disintegrable or easily rupturable envelope or container containing the tooth paste, the paste being released either by dissolution of 15 the envelope when the device is wet or rupture of the envelope by the bending of the finger.

Other objects of the invention will appear as the following description of a preferred and practical embodiment thereof proceeds.

20 In the drawing which accompanies and forms a part of the following specification and throughout the several figures of which the same characters of reference have been employed to designate identical parts:

25 Figure 1 is a perspective view of the device of the invention positioned upon the finger;

Figure 2 is a perspective view of the device when not in use;

Figure 3 is a cross section showing the tooth 30 paste in a soluble or easily rupturable capsule;

Figure 4 is a longitudinal section illustrating the tooth paste in a rupturable envelope;

Figure 5 is a longitudinal section illustrating the method in which the envelope shown in Figure 4 is distorted to open the seam and loosen the tooth paste; and

Figure 6 is a cross section taken along the line 6—6 of Figure 4.

Referring now in detail to the several figures 40 the numeral 1 represents a finger cot which may be of rubber or any suitable textile fabric and being provided with a tab 2 which when the cot is upon the finger may be pressed by the thumb as shown in Figure 1 in order to hold the cot in place. The tab may be provided with a hole 3 facilitating the hanging up of the device when not in use.

The side of the finger cot is provided with a 45 rubbing strip 4 preferably formed of a rough, but reasonably soft fabric of which turkish toweling may be considered an example. The strip 4 is attached to the finger cot in any suitable manner as by the stitching 5 shown in Figure 3.

Since the present invention contemplates the 50 use of tooth paste instead of powder as a cleansing agent, means are provided for containing

the tooth paste which shall be impervious before the device is used, but which will disintegrate making the tooth paste available. The device is designed to be dipped in water while on the finger and to be rubbed against the gums and teeth, the released tooth paste passing through the meshes in the fabric strip 4, permeating the same and making contact with the teeth.

The receptor for the tooth paste may be of 10 any desired construction having the qualities of initial imperviousness and subsequent disintegrability or rupturability. Figures 1 and 3 show a water soluble or rupturable gelatinous capsule 15 filled with tooth paste and the walls of which will soften when the device is dipped in water permitting the capsule to be readily ruptured by slight pressure against the teeth, releasing the tooth paste.

Figure 6 shows a modified form of receptor 20 comprising a small flat envelope 1 of impervious substance such for example, cellophane having a weak rupturable zone constituted by the seam 8. The seam side of the envelope of course faces the detergent strip 4. Either before or after the 25 device is dipped in water, the finger is bent as shown in Figure 5 distorting the envelope so as to open the seam 8 and release the tooth paste.

While the invention contemplates primarily a dental cleaning and massage device containing 30 the receptor of tooth paste and packaged in a sanitary manner and designed to be used but once, it is within the purview of the invention to provide that the device shall be used repeatedly. To this end, the upper end 9 of the detergent 35 strip 4 may be left unsecured to the finger cot forming the mouth of an open pocket into which a fresh capsule or envelope may be slipped daily, or as often as the teeth are cleaned.

While I have in the above disclosure described 40 what I believe to be a preferred and practical embodiment of the invention, it is to be understood that the details of construction as shown and described are merely by way of example and not as limiting the scope of the invention as defined in the terms of the appended claim.

What I claim is:

A dental cleansing and massaging device comprising a flexible finger cot, a rubbing strip extending longitudinally along one side thereof, a 50 fragile disintegrable container having a tooth cleaning preparation therein, said container positioned beneath the strip and adjacent the wall of the finger cot, said strip forming a protective covering for said container.

HARRY LOGUE WELKER.
